Primary Examiner—Freda S Nunn

(57) **CLAIM**

The ornamental design for a laptop computer, as shown and described.

DESCRIPTION

FIG. 1 depicts a left front perspective of a laptop computer with a closed cover;

FIG. 2 depicts a left elevation of the laptop computer with a closed cover;

FIG. 3 depicts a left elevation of the laptop computer with an open cover;

FIG. 4 depicts a left front perspective of the laptop computer with an open cover;

FIG. 5 depicts a right rear perspective of the laptop computer with an open cover; and,

FIG. 6 depicts a bottom plan of the laptop computer.

The broken lines showing of the input ports and output ports disposed on the sides of the article are for the purpose of illustrating the article and form no part of the claimed design.

The broken lines showing the compartment cover, feet, and fasteners disposed on the bottom of the article are for the purpose of illustrating the article and form no part of the claimed design.

The broken lines showing the keyboard are for the purpose of illustrating the article and form no part of the claimed design.
